UNITED STATES PATENT OFFICE.

PETER J. PAULY, OF ST. LOUIS, MISSOURI.

JAIL-DOOR-LOCKING MECHANISM.

Application filed October 5, 1925. Serial No. 60,518.

To all whom it may concern:

Be it known that I, PETER J. PAULY, a citizen of the United States, residing at St. Louis, State of Missouri, have invented certain new and useful Improvements in Jail-Door-Locking Mechanism, of which the following is a specification.

My invention has relation to improvements in jail door locking mechanism and 10 consists in the novel features of construction more fully set forth in the specification and pointed out in the claims.

Briefly, the invention consists in a locking mechanism for a jail door, said mechanism 15 being enclosed within a suitable case adjacent to which the door is mounted, said door being adapted to receive a plurality of locking bolts which are mounted within the case and project through the wall thereof 20 for the purpose of engaging the jail door. The locking bolts are accessible only from inside of the case which is provided with a door carrying a combination lock so that it may not be opened by anyone other than the 25 turnkey or custodian of the jail.

It is thus among the objects of the invention to provide a jail door locking mechanism which is as nearly absolute proof against jail delivery as human ingenuity can 30 make it. A further object is to provide a locking mechanism for doors which is secured against dislodgment by a device within the case housing the mechanism, said device associated with the door within the case 35 so that under no circumstances can the locking mechanism be operated unless the case door is open. Further and other advantages will be better apparent from a detailed description of the invention in connection with the accompanying drawings in 40 which—

Figure 1 is a plan of a jail building showing the arrangement of the cells and other rooms together with their respective doors; 45 Figure 2 is a vertical, longitudinal section taken on the line 2—2 of Fig. 1 showing the jail partition and cell doors in section; Figure 3 is a section view looking from the end of the jail corridor into the case housing 50 the locking mechanism, the door of said case being open; Figure 4 is a vertical cross section taken on the line 4—4 of Fig. 3 with the case omitted and parts broken away; Figure 5 is a horizontal cross section taken 55 on the line 5—5 of Fig. 3; Figure 6 is a vertical cross section taken on the line 6—6 of Fig. 3; Figure 7 is a horizontal cross sectional detail taken on the line 7—7 of Fig. 3; Figure 8 is a cross sectional detail taken on the line 8—8 of Fig. 4, the locking bar being shown in position when the locking bolts are free to be moved; Figure 9 is a cross sectional detail similar to Fig. 8, the locking bar, however, having been dropped into engagement with the locking bolts and also with the lock pin of the door 60 operated trigger.

Referring to the drawings, 1 represents the case or box for housing the locking mechanism which is provided with a door 70 2 adapted to be locked by means of a combination lock 3. The box is mounted in the guards' corridor C in line with partition P in which are the cell doors D, D' and the door D'' leading to the safety vestibule V. 75 The safety vestibule is also provided with a door d leading to an assembly or dining room A, the door d, it will be observed, being disposed at right angles to the cell doors D, D' and D''. Between the guards' corridor C and prisoners' corridor C' is a hinged door d', said door being adjacent to the box 1 and being adapted to close against a bar 4 in closely fitting relation with the side 5 of said box. A plurality of locking 80 bolts 6, 6, 6' connected together by a bar 7 are disposed within the box 1, and their ends adjacent to the door d' are arranged to operate through the wall 5 of the box, the opposite ends of bar 6, 6 being mounted in 85 openings o, o of brackets 8, 8 secured to the rear wall 9 of the box. An angle bar 10 is secured against the rear wall 9 of the box in spaced relation with the brackets 8, 8 and a locking bar 11 is positioned between the 90 angle bar 10 and brackets 8, 8, said plate 11 being provided with openings 12, 12, 12 to receive the ends of the locking bolts 6, 6, 6', the latter being provided with notches 13, 13, 13 on their upper surfaces to receive the 95 upper margins of the openings 12 for holding the locking bolts in locked position as will be better apparent hereinafter. A spring s is disposed on each bolt 6 between a collar b and the bracket 8, said spring 100 operating to exert pressure on the bolts 6, 6, 6' thus keeping them in their outermost positions (Fig. 3).

When the bolts 6, 6, 6' are in their normal locking position, they project through suitable openings in the wall 5 of the box 1, and are locked in this position by means of the locking bar 11 which drops downwardly so that the openings 12 therein engage the notches 13 in said bolts. However, the bar 11 is only free to descend when the door 2 is closed because of the trigger 14 which is 5 acted upon by a lug 15 secured inside the door, the inner end 14' of said trigger operating a lock pin 16 mounted between ears 17, 17 and traversing the bar 11 (Fig. 4). When the door 2 is closed the trigger is 10 moved inwardly by lug 15 to a position that will bring said bar in register with a notch 18 on the upper side of the pin 16, thus permitting the bar 11 to descend into said notch. When the door 2 is opened and the 15 lug 15 withdrawn from the trigger 14, said trigger is free to assume the position shown in Fig. 5 under the influence of a coiled spring 19 disposed about pin 16 between one of the ears 17 and the lever arm 14. 20

25 A disc 20 is rotatably mounted on the inside of wall 5 and somewhat spaced from said wall, the disc being provided with a handle 21 whereby the same is rotated and a slide bar 22 is slidingly mounted on the 30 inner surface of said wall 5, said slide bar having a stud 23 projecting from it into a slot 24 in the disc 20. The inner end of slide bar 22 is connected to one arm of a bell-crank lever 24', the opposite arm of 35 said bell-crank lever being connected to a bar 25 which is rigidly secured to the bar 7 connecting the bolts 6. Therefore, if the disc 20 is rotated in the direction of the arrow (Fig. 6), slide bar 22 will be moved 40 inwardly, thus rocking the bell-crank so as to move the bar 25, and, of course, bar 7 and bolts 6, 6, 6' to withdraw said bolts from the openings 26 in the marginal bar 27 of the door d'. A connecting link 28 is 45 connected at one end to disc 20 opposite to the point where said disc makes connection with the slide bar 22, said link being connected on the opposite end to one arm of the bell-crank lever 29, the opposite arm of said bell-crank lever having one end of the connecting link 30 secured to it, the link 30 being connected at its opposite end to the depending arm of a bell-crank lever 31, the laterally 50 projecting arm of said bell-crank lever having a stud 32 projecting from it in proximity to a boss 33 on the lock plate 11. The purpose of this last described mechanism being to lift the locking plate 11 by rotating the disc 20 in the direction opposite to the arrow (Fig. 6) thereby raising the stud 32 and forcing the lock plate 11 upwardly. Of course, when the trigger 14 is in the position shown in Fig. 7 with the door 2 closed, it is impossible to move the disc 20 to a position 55 for raising the lock bar 11 because said

lock bar is held against movement by the pin 16 as heretofore explained. The locking bolts 6, 6, 6' cannot be forced inwardly by pressure against them by their outer ends when the locking plate is in its normal position in engagement with the notches of said bolts, and when the door 2 is closed, it is obviously impossible to release said locking plate in any way from its engagement with the locking bolts. Thus when the door of 75 the box 1 is closed, there is no way to open the door d'.

Having described my invention I claim:

1. In combination with a door, a locking mechanism therefor comprising a plurality 80 of locking bolts adapted to enter suitable openings in the margin of said door, said locking bolts being provided with notches in aligning relation, a lock bar transversely disposed with relation to the locking bolts 85 and provided with a plurality of openings adapted to be traversed by said bolts, said lock bar being longitudinally movable to permit engagement of the margins of the openings with the notches in the locking bolts to hold the same against movement, an operating handle for the locking bolts, suitable connections between said handle and the bolts, and suitable connections between said handle and the aforesaid locking bar, said handle being movable in a given direction 90 to release the locking bar from the bolts and movable in an opposite direction to effect a release of the bolts from the door. 95

2. In combination with a door and locking mechanism therefor, a suitable case for said locking mechanism, a door for said case, said locking mechanism comprising a plurality of locking bolts adapted to enter suitable apertures in the margins of the first mentioned door, a lock bar adapted to hold the locking bolts against movement, a trip lever for securing the lock bar in locked position, means on the case door for cooperating with the trip lever when said door is closed to prevent a release thereof, and means within the case effective on the trip lever to release the lock bar when the case door is open, said last mentioned means being also associated with the lock bolts to effect a withdrawal of said bolts from the door locked thereby. 110

3. In combination with a jail door, a locking mechanism therefor, a case enclosing said locking mechanism, and a door for said case, said locking mechanism comprising a bolt movably mounted in the case to engage the door for locking the same, means associated with the case door for securing the bolt against movement when in its position of engagement with the jail door, means for releasing the securing means when the case door is open, and means for disengaging the locking bolt from the jail door. 115

4. In combination with a jail door, a lock- 120

ing mechanism therefor, a case enclosing said locking mechanism, and a door for said case, said locking mechanism comprising a bolt movably mounted in the case to engage
5 the door for locking the same, means partly within the case and partly on the case door for securing the bolt against movement when in its position of engagement with the

jail door, means for releasing the securing means when the case door is open, and
10 means for disengaging the locking bolt from the jail door.

In testimony whereof I hereunto affix my signature.

PETER J. PAULY.
